UNITED STATES PATENT OFFICE.

GEORGE SEMLER, OF NEW YORK, N. Y., ASSIGNOR TO GEO. BORGFELDT & CO., OF NEW YORK, N. Y., A CORPORATION OF NEW JERSEY.

DESIGN FOR A NOVELTY CANDY-CONTAINER OR BANK.

48,131.

Specification for Design.

Patented Nov. 9, 1915.

Application filed July 13, 1915. Serial No. 39,689. Term of patent 3½ years.

To all whom it may concern:

Be it known that I, GEORGE SEMLER, a citizen of the United States, residing in the borough of Manhattan, county, city, and State of New York, have invented a new, original, and ornamental Design for a Novelty Candy-Container or Bank, of which the following is a specification, reference being had to the accompanying drawing, forming a part thereof, and in which—

The figure is a perspective view of a novelty candy container or bank showing my new design.

I claim—

The ornamental design for a novelty candy container or bank as shown.

GEO. SEMLER.
